UNITED STATES PATENT OFFICE.

MARSHALL B. LLOYD, OF MENOMINEE, MICHIGAN, ASSIGNOR TO HEYWOOD-WAKEFIELD COMPANY, OF BOSTON, MASSACHUSETTS, A CORPORATION OF MASSACHUSETTS.

METHOD OF AND MEANS FOR PRODUCING THREADS, STRANDS, WIRE, AND THE LIKE.

Application filed January 12, 1922. Serial No. 528,674.

To all whom it may concern:

Be it known that I, MARSHALL B. LLOYD, a citizen of the United States, and a resident of Menominee, Michigan, have invented a certain new, useful, and Improved Method of and Means for Producing Threads, Strands, Wire, and the like, of which the following is a specification.

While my invention may be used for a number of different purposes, I am concerned primarily with the manufacture of fibrous strands. I shall, therefore, dwell particularly upon that subject. This, however, I wish to be considered as by way of illustration, and not by way of limitation.

A typical example of such a fibrous strand is the so-called fibre reed. Fibre reed is a product which is very extensively used in the manufacture of baby carriages, furniture, and the like and is formed by passing a ribbon of paper through a die, meantime rapidly twisting the paper to form the ribbon into a mass of such form that it can be properly compacted by the die in its passage therethrough.

Fibre reed is made in various sizes and in numerous cross-sectional shapes, and in some instances, the paper ribbon is first immersed in glue and then twisted, and other instances the paper is merely tightly twisted and then compacted by passage through a die.

A fibre reed article, such as a piece of furniture or a baby carriage is composed of many lineal feet of fibre reed material and the manufacture of these articles has been reduced to such a state that it is very desirable that the fibre required for the manufacture of a given article shall always be of a given weight because the material is sold by the pound. It is also desirable that the size of the fibre strands shall be uniform as this affects the appearance.

Great difficulty has been encountered in the proper manufacture of fibre reed strands for the reason that the paper, because of its abrading character, very quickly wears the surface of even the most hardened steel die. A hardened steel die, such as has heretofore been used, wears away to such an extent that within four or five hours it must be discarded and a new die inserted. From the

time the die is put into operation until it is discarded the fibre strand is made progressively larger due to the progressively enlarging die opening, with the result that a much larger amount of paper is placed into a given numeral of feet of the strand than is desired. In the course of the production of reed articles, on the scale on which it is carried-on, in manufacturing plants, this excess weight, which is undesirably embodied in the material, amounts to a very substantial amount, indeed.

It is an object of my invention to provide a method whereby fibre reed or other strands can be produced which shall be of uniform cross-sectional area.

Another object of my invention is to provide means wherewith it shall be possible, upon a practical commercial scale, to produce fibre reed or other strands that shall be of substantially uniform cross-sectional area throughout.

Again it is an object of my invention to provide a method for the production of strands of substantially uniform cross-section which shall be automatic in its operation.

Other objects of my invention, are to provide means which shall require little attention; to provide a die construction which shall be less expensive and of greater durability than dies heretofore devised for that purpose; and generally to simplify and cheapen the cost of production of strand material and the articles produced therefrom.

My invention will be more readily understood by reference to the accompanying drawings which illustrate what I consider, at the present time, to be the best embodiment thereof.

In said drawings:

Fig. 1, is a general view, in elevation, illustrating the conversion of a ribbon of material into a strand, under my invention.

Fig. 2, is a top plan view of the die through which the ribbon of material passes.

Fig. 3, is a detailed view of the die substantially on the line 3—3 of Fig. 1.

Fig. 4, is a vertical cross-sectional view through the die taken substantially on the line 4—4 of Fig. 2.

Fig. 5, is an enlarged sectional view showing the wire member that forms the die opening.

- Fig. 6, is a general view, in elevation, of 5 a modification of my invention in which automatic means are provided for maintaining the proper cross-sectional area of the strand, some of the parts being shown diagrammatically; and 10 Fig. 7, is a plan view of the mechanism shown in Fig. 6.

As stated in the opening of the specification, I am primarily interested, at the present time, in the manufacture of fibre reed 15 strands and for that reason, and because it is sufficiently illustrative, will limit my description to the production of such materials.

Referring to the drawings: 1, represents 20 a ribbon of paper which is withdrawn from the spool 2, and which in some instances passes under a roller 3, thereby dipping into a receptacle 4, containing a glue size. As here shown, the ribbon 1, then passes over a 25 roller 5, and into a die 6, from which it emerges as a tightly compacted hard strand 7. It should, here, be added that the strand 7 is being rapidly twisted, (by mechanism not shown) so that the paper is very tightly 30 twisted when it emerges from the die. It is not necessary to illustrate the twisting mechanism because this may be of usual or desired construction, and as a matter of fact the same may be said with respect to the 35 spools containing the paper, the sizing mechanism, and the like. I have designed my novel die mechanism so that it may be inserted in the place of the die mechanism heretofore employed in such manufacturing 40 processes. It should also be understood that the paper may not be sized unless desired.

The die mechanism 6, as here shown, comprises a block member 8, which has a relatively large central opening 9, and which is 45 provided with a bell-shaped mouth 10, in order to avoid any danger of tearing the paper ribbon as it enters the opening 9. At the other end will be found a centrally arranged cylindrical member 11, a portion 12, of which extends beyond the member 8, and 50 forms a bearing for the worm wheel 13. The member 11 is provided with a conical central opening in which is arranged a spiral wire member 14, one end 15, of which projects outwardly and is held in a slot 16 provided, therefor, in the member 8, and the other end 17, of which extends into a slot 18 provided therefor, in the block 19. The 55 block 19, is secured in the worm wheel 13 so that it rotates therewith, and to permit easy assembly of the parts, the block 19 is 60 removably secured by means of a screw 20. In this manner the die surface is provided with a large entrant opening 21, a small exit 65 opening 22, and an opening of progressively

changing size therebetween. By rotating the worm wheel 13, in one direction it is possible to diminish the size of the exit opening 22 and by rotating it in the opposite direction to enlarge the size of that opening. As will 70 be shown shortly, this feature is of great importance for several reasons.

For turning the worm wheel 13, I provide a worm 23 which is rotatably mounted in block 24 secured, by means of screws 25, 75 to the member 8. A shank portion 26 extends away from the block 24 and terminates in the disk 27 convenient for hand turning. This worm and worm wheel construction enables a very accurate and minute adjusting or regulation of the die surface. In the manufacture of the die surface the wire need only be formed substantially to size, after which the die surface or opening can 80 be accurately changed or adjusted, as may be required, for the production of a strand of predetermined size. This eliminates the necessity of extremely accurate manufacture of the die such as is required in the production of the solid dies heretofore used. Again 85 it enables the production thereof more rapidly, with unskilled labor and at little cost.

So much for the initial production of the die.

In operation the die is of even greater 90 value for the reason that it becomes possible to produce continuously a strand of substantially, unvarying, cross-sectional area. This is not possible with the more 95 expensive and less efficient dies, heretofore employed. I might, here, add that the wire which I prefer to use in the spiral that forms the die surface is a high grade piano wire. Of course the wire die surface wears 100 away in use, but not rapidly, and the workman tending the machine gages the fibre strand from time to time and when it is 105 found that the strand is slightly oversize a partial turn of the wheel 27, in the direction of the arrow, serves to reduce the size 110 of the opening 22, or rather to restore it to its initial desired size. This adjustment may be continued from time to time, as may be required, until the die has worn to such an extent as to be no longer usable, at which 115 time the wire die can be quickly removed and a new wire die easily supplied. I might, here, add, that the wire die can be produced at about one-fiftieth of the cost 120 of the solid die heretofore in general use and that its useful life, under like conditions, is about three times that of the solid die.

While graduations may be placed upon 125 one of the rotating parts regulating the die to indicate the size of the die opening, I do not deem this necessary since the workman can readily gage the strand as it emerges, without difficulty.

My invention contemplates complete au- 130

tomatic operation and I have illustrated in Figs. 6 and 7, mechanism adapted to accomplish such operation. All of the parts which are similar to the parts of Figs. 1 to 5 have been given like reference characters and it will be understood that the die surface and the general operation of the die is the same. In this instance, instead of depending upon the gaging of the strand 7, 10 from time to time, by the workman, and upon the workman manually adjusting the die opening by turning the wheel 27, I provide an automatic device or gage which controls the die opening. That is to say that 15 if the die opening becomes enlarged, due to wear, and the emerging strand is therefore oversize, the gage, through means shortly to be described, reduces the size of the die opening to that required to produce a strand 20 of desired cross-sectional area.

The mechanism shown in Figs. 6 and 7 for accomplishing this purpose comprises two rolls 28 and 29. The lower roll 28 is held against anything but rotary motion. 25 The upper roll 29 is rotatably mounted in a long lever 30 close to the pivot 31 thereof. The outer end of the lever 30 is provided with a contact plate 32 which when the gage rolls 28 and 29 are the desired distance apart, i. e. when the strand 7 is of desired cross-sectional size, is out of contact 30 with the terminals 33 and 34 of the electric wires 35 and 36 that are connected respectively to the solenoid 37 and the electric 35 battery or other source of electrical energy 38. The lower end of the solenoid core 39' is pivotally joined at 40 to a lever 41, which in turn, is pivotally joined at 42 to the axis of the ratchet wheel 43, which ratchet wheel 40 functionally corresponds to the hand wheel 27, heretofore described. That is to say, when the ratchet wheel 43 is turned the size of the wire die surface or opening is changed and when the ratchet wheel 43 is 45 moved in the direction of the arrow (see Fig. 6) the size of the die opening is reduced and it is this action that is desired when the filler strand becomes larger than is desired. To accomplish this purpose I 50 pivot a pawl 44 to the lever 41 and hold it in contact with teeth 43' of the ratchet wheel 43 by means of a spring 45. Thus upward swinging movement of the lever 41 causes turning movement of the ratchet wheel 43 in the direction of the arrow with the resultant diminution in the size of the die opening. Let us assume, now, that the 55 filler strand 7 as a result of the die opening being enlarged, by wear or otherwise, emerges slightly larger than is desired. This being the case the roll 39 is raised lifting the lever 30 and causing the contact block 32 thereof to engage the electric terminals 33 and 34 thus closing the circuit, 60 energizing the solenoid and raising the sole- noid core 39' and the lever 41 to which it is attached. As before stated this causes the rotation of the ratchet wheel resulting in the reduction of the size of the die opening and obviously reducing the size of the filler 70 strand, as desired. Immediately the filler strand is reduced in size, the lever 30 drops thereby drawing the contact block 32 away from the terminals 33 and 34 and breaking the electrical circuit which deenergizes the 75 solenoid, thereby permitting the core 39' to fall, by gravity, thus restoring the lever 41 to its initial position so that it can again be raised, in like manner, so soon as the filler strand reaches an undesired oversize, which 80 oversize obviously can be regulated within such practical limits as may be found to be necessary or advisable.

Since this disclosure will readily suggest to others modified methods and means 85 whereby the substantial objects and purposes of my invention may be attained, I do not wish to be limited to the specific mechanism herein shown and described, nor to the precise state of the method or the 90 stated sequence thereof, except only as may be necessary by limitations in the hereunto appended claims.

I claim:

1. A die formed of a conical spiral coil of material.
2. A die formed of a conical spiral coil of wire.
3. A die formed of a conical spiral coil of material cylindrical in cross section.
4. A die formed of a conical spiral coil of hard wire with the convolutions arranged in engagement with each other.
5. A die formed of a coil of hard wire, said coil being of a conical spiral formation at one end.
6. A die formed of a conical spiral coil and having a centrally disposed opening, and means for engaging parts of said coil for adjusting the size of said opening.
7. A die formed of a conical spiral coil having a tapering opening presenting an unbroken annular surface.
8. A die formed of conical spiral coil having a tapering opening presenting an unbroken annular surfaces, and means for contracting the coil for affecting an adjustment of said tapering opening.
9. The method of making a strand of substantially uniform, cross-sectional area that consists in providing material of which the strand is to be formed, passing the material through an adjustable die opening and in using the emerging strand to regulate the size of the die opening.
10. The method of making a strand of substantially uniform, cross-sectional area that consists in providing material of which the strand is to be formed, passing the material through a die opening, and in suc- 130

- sively restoring the die surface by adjustment of the die itself, at it wears, to such size as will produce the desired sized strand by using the emerging strand to regulate said 5 adjustment.
11. Means for producing a strand of substantially uniform cross-sectional area comprising a die having an adjustable die surface, means positioned in the path of the 10 completed strand, for adjusting the size of the die opening, said means being operable by engagement with the completed strand.
12. A die embodying therein a stationary member, a rotatable member, and a conical 15 spiral coil having one end fixed in the stationary member and the other in the rotatable member.
13. A die embodying therein a stationary member, a rotatable member, a conical spiral 20 coil having one end fixed in the stationary member and the other in the rotatable member, and means for rotating the rotatable member.
14. A die embodying therein a stationary member, a rotatable member, a conical spiral 25 coil having one end fixed in the stationary member and the other in the rotatable member, and worm gear mechanism for imparting desired rotation to said rotatable 30 member.
15. A die embodying therein a stationary member, a rotatable member, a conical spiral coil having one end fixed in the stationary
- member and the other in the rotatable member, worm gear mechanism for imparting 35 desired rotation to said rotatable member, and ratchet mechanism for actuating said worm gear mechanism.
16. A die embodying therein a stationary member, a rotatable member, a conical spiral 40 coil having one end fixed in the stationary member and the other in the rotatable member, ratchet mechanism for rotating said worm gear mechanism, and a solenoid for operating said ratchet mechanism. 45
17. A die embodying therein a stationary member, a rotatable member, a conical spiral coil having one end fixed in the stationary member and the other in the rotatable member, ratchet mechanism for rotating said 50 worm gear mechanism, a solenoid for operating said ratchet mechanism, and means for energizing and deenergizing said solenoid.
18. A die formed of a continuous length 55 of wire arranged in a conical spiral coil with the convolutions in engagement with each other throughout the entire coil, the ends of said wire projecting beyond the last convolutions in planes at a right angle to the axis 60 of said coils to provide means by which the coil may be tightened to reduce its diameter throughout its length.

In testimony whereof, I have hereunto set my hand, this 30th day of December, 1921.

MARSHALL B. LLOYD.
